UNITED STATES PATENT OFFICE.

FREDERICK JOSEPH RADLER, OF JERSEY CITY, NEW JERSEY.

HOSE-NOZZLE.

No. 906,287.

Specification of Letters Patent.

Patented Dec. 8, 1908.

Application filed August 8, 1906. Serial No. 329,679.

To all whom it may concern:

Be it known that I, FREDERICK J. RADLER, a citizen of the United States, and a resident of Jersey City, in the county of Hudson and State of New Jersey, have invented a new and Improved Hose-Nozzle, of which the following is a full, clear, and exact description.

This invention relates to improvements in water-hose nozzles, and its connections are particularly adapted for use with hose on fire water-towers, stand-pipes and the like, the object being to provide a nozzle with connections whereby it may be readily turned in various directions, the connections being so constructed that no leakage can occur at the joint.

I will describe a hose nozzle embodying my invention and then point out the novel features in the appended claim.

Reference is to be had to the accompanying drawings forming a part of this specification, in which similar characters of reference indicate corresponding parts in all the figures.

Figure 1 is a side elevation of a hose nozzle and its connections, embodying my invention; Fig. 2 is a plan thereof; Fig. 3 is a section on the line *x—x* of Fig. 2; Fig. 4 is a section on the line *y—y* of Fig. 3.

Referring to the drawings, 1 designates the nozzle attached to a barrel 2 having rotary movement in a casing 3. The said casing 3 has cylindrical body with a slot 4 which extends circumferentially, and through which the nozzle 1 passes, the slot of course, permitting the nozzle to be swung circumferentially of the casing. The barrel 2 has an inlet slot 5 through which water passes to the nozzle and to permit the water to pass freely through said slot as said nozzle is in any of the suggested positions, the casing at one side is depressed to form a chamber 6 which projects laterally from the cylinder of the case, as shown. Seated in the channels formed in the wall of the casing adjacent to said chamber, are packing strips 7 which will prevent leaking of water between the barrel and casing. The barrel 50 extends practically the full length of the casing and removably engaging with the ends of the casing are caps 8, which cover the heads of the barrel; and packing material 9 is placed in the caps to engage snugly 55 against the ends of the barrel, thus preventing leakage at these points. The casing 3

has screw-thread connection with a hose coupling consisting of a short tubular neck 10, with the outer end of which a ring 11 removably connects as here shown, the connection being made by screw-threads; and on this ring 11 is an annular flange 12 for engaging in the channel 13 formed in the inner side of a collar 15, and with this collar 15 a hose coupling ring 16 has screw-thread engagement. Between the rings 11 and 16 a packing 17 is placed.

In the drawings I have shown the invention as attached to a water-tower or ladder 18, which of course, is to be supported on the usual truck. As a means for attaching the device to the ladder, a frame or arm 19 is secured to a rung of the ladder as here shown, by means of clips 20, and on this frame or arm is a ring 21 which surrounds the tube 10 between the annular shoulder 22 on said tube and the end of the interiorly threaded section 23 on the casing 3. A rod 24 extends upward from the frame or arm 19 through a frame or arm 25 attached to a rung of the ladder, and on the upper end of this rod 24 is a pulley 26, over which halyards 27 pass, the said halyards being attached to lugs 28 on opposite sides of the nozzle, and the said halyards may extend down to the ground so that the nozzle may be turned from such a point; that is, by pulling on one of the halyards the nozzle may be pulled into different positions. By pulling upon both halyards the nozzle may be moved with relation to the casing 3, or circumferentially thereof. On the frame or arm 25 are spring fingers 29 designed to receive and hold the nozzle, when not in use, as clearly indicated by dotted lines in Fig. 1 and full lines in Fig. 2. Of course when the casing carrying the nozzle is turned laterally, the turning will take place between the ring 11 and the collar 15, and such turning in connection with the movements of the nozzle relatively to the casing as before mentioned, makes practically a universal joint connection between the nozzle and a hose.

It will be observed that the two packing strips 7 are disposed substantially diametrically opposite to each other in the wall of the case; the slot 4 extends around on one side of the case, its ends being disposed near the packing strips; the water chamber 6 is formed on the opposite side of the case; the upper side of this chamber extends nearly

to the upper packing strip while the lower side extends nearly to the lower packing strip. In this way two narrow bridges, as it were, are formed in the wall of the case 5 beyond the ends of the slot 4. In one extreme position of the nozzle 1, as shown in Fig. 3, the upper edge of the inlet slot 5 is substantially in alinement with the upper wall of the water chamber; in the other extreme position of the nozzle the lower edge 10 of the slot 5 is substantially in alinement with the lower edge of the water chamber. From this arrangement it will be seen that I obtain a great range of movement for the 15 nozzle.

Having thus described my invention I claim as new, and desire to secure by Letters Patent:

In combination, a case having a cylindrical body and an enlarged water chamber formed 20 on the side thereof, a tubular neck communicating with said water chamber and adapted

to lead water thereto, said body having a circumferential slot in the wall thereof opposite said water chamber, a barrel rotatably 25 mounted in said cylindrical body, a nozzle attached to said barrel and projecting through said slot, said barrel having an opening in the wall thereof opposite said nozzle and communicating with the interior 30 of said chamber, longitudinally disposed packing strips mounted in the wall of said body near said water chamber, said barrel having heads closing the ends thereof, caps 35 removably mounted on the ends of said cylindrical body, and packing disks under said caps seating on said heads.

In testimony whereof I have signed my name to this specification in the presence of two subscribing witnesses.

FREDERICK JOSEPH RADLER.
